UNITED STATES PATENT OFFICE.

LEWIS T. HOUGHTON, OF WORCESTER, MASSACHUSETTS.

MECHANISM FOR RECIPROCATING PLANER-BEDS OR SIMILAR PURPOSES.

1,014,706.

Specification of Letters Patent. Patented Jan. 16, 1912.

Application filed July 6, 1905. Serial No. 268,484.

To all whom it may concern:

Be it known that I, LEWIS T. HOUGHTON, a citizen of the United States, residing at Worcester, in the county of Worcester and State of Massachusetts, have invented a new and useful Mechanism for Reciprocating Planer-Beds or for Similar Purposes, of which the following is a specification.

This invention relates to an improved mechanism for converting rotary motion into rectilinear reciprocating motion.

The especial object of this invention is to provide an improved construction adapted for reciprocating the tables of metal planing machines, or for other machinery.

To this end this invention consists of the parts and combinations of parts as herein-after described and more particularly pointed out in the claims at the end of this specification.

In the accompanying two sheets of drawings, Figure 1 is a bottom plan view partly in section of sufficient parts of a metal planing machine to illustrate the application of this invention thereto. Fig. 2 is a sectional view taken on the line 2—2 of Fig. 1. Fig. 3 is a detail sectional view taken on the line 3—3 of Fig. 1. Fig. 4 is a bottom plan view partly in section of sufficient parts of a metal planing machine to illustrate the application of this invention to a metal planer in which a single driving rack and pinion are used, and Fig. 5 is a side view of the construction shown in Fig. 4.

In ordinary machine-shop practice one of the least satisfactory operations is the finishing of flat metallic surfaces. This work is ordinarily done on metal planing machines of that class in which the work is mounted on a reciprocating table, and is moved back and forth under the cutting tool which is fed transversely between the successive strokes of the planer-table. In the use of this class of machines the speed of operation is limited by the shock and jar incident to reversals of the motion of the planer table, and the character of the work is frequently injured by the shock and jar resulting when the cutting tool first strikes the edge of the block of metal being planed or finished.

In this class of machines as now ordinarily used the reversals of the direction of travel of the table are usually accomplished by the shifting of belts on a set of tight and loose pulleys. In order that reversals may be effected promptly it is necessary to use narrow driving belts, and these belts must travel at high speed in order that sufficient power may be transmitted to the planer table to do the required work.

The especial object of my present invention is to provide a reciprocating mechanism in which the jar or shock of the reversal of the bed can be compensated for by a yielding connection between the driving pinion and bed. This yielding connection is also of advantage in overcoming jar or shock due to the first impact of the cutting tool with the block of metal being planed.

While my invention has been especially designed for use in metal planers, it is to be understood that the same is also applicable to various other machines in which heavy or cumbersome parts are required to be reciprocated.

The yielding connection which I interpose between the driving pinion and the table or part to be reciprocated comprises a cylinder and piston. When the motion of the table in one direction terminates and the bed is to be started in the opposite direction the piston is forced into the cylinder. The cylinder preferably contains a liquid, such as oil, and the outlet from the cylinder is restricted so that the travel of the piston will give the desired yielding action or lost motion to prevent jar or shock due to the reversals of the bed, and the piston preferably will not reach the end of its travel until after the cutting tool has engaged with and started its cutting operation, whereby this yielding connection provides for the commencement of the cutting operation at a somewhat reduced speed, thus diminishing the shock and jar which sometimes result from tool impact.

In practice in order to cushion the reversal of the table at the opposite ends of the stroke, I preferably employ two opposed cylinders which are connected by a restricted

pipe or passage, and I prefer to put a throttling valve in this pipe or passage to regulate the flow of the liquid to vary the cushioning effect to any desired degree.

- 5 Referring to the accompanying drawing for a detail description of one form of apparatus embodying this invention, as shown in Fig. 1, 10 designates a driven part in the form of the bottom side of an ordinary planer table and 11, 12 and 13 designate the uprights or posts forming part of the framework of the machine. The driving connections for moving the planer table 10 in one direction comprise a shaft 14 journaled in the uprights 11 and 12, a pulley 15 fastened rigidly upon the shaft 14, and a driving pinion 16 which is mounted loosely on the shaft 14. The hub of the driving pinion 16 is provided with clutch teeth coöperating with a clutch-piece 17 splined upon the shaft 14. The driving pinion 16 meshes with a rack 18 which is loosely mounted in the planer table 10, and preferably fits into dove-tailed ways therein as shown in Fig. 3. A similar set of devices are used for moving the planer table in the opposite direction, comprising a shaft 22 journaled in the posts 12 and 13 with a pulley 23 fastened rigidly thereto, and a driving pinion 24 loose thereon. The hub of the driving pinion 24 is provided with clutch teeth coöperating with the teeth of a clutch-piece 25 splined on the shaft 22. The driving pinion 24 meshes with a rack 27 which is mounted loosely in the planer-table in the same manner as the rack 18. The clutch pieces 17 and 25 are connected by a yoke 26, which yoke may be shifted by any of the ordinary automatic reversing devices which need not be herein shown or described.

The parts as thus far referred to constitute a well-known type of planer driving mechanism.

Referring now to the yielding connection which I employ between the table and its racks, 19 designates a piston rod extending from the rack 18. Fastened on the piston rod 19 is a piston 20 mounted in a cylinder 21. Extending from the end of the rack 27 is a piston rod 28 carrying a piston 29 fitting into the cylinder 30. The cylinders 21 and 30 are opposed to each other and said cylinders are connected by a pipe or restricted passage 31 containing a throttling valve 32.

In the use of a complete metal planer as thus constructed it will be seen that when the driving pinion 16 is thrown into operation it will tend to force the piston 20 back into the cylinder 21, and that the travel of said piston will be opposed by the resistance of liquid forced out of the cylinder through its restricted outlet. This will provide a cushioning effect which will prevent the sudden shock or jar due to a too sudden reversal,

and will also permit the commencement of a cutting operation before the bed reaches its full speed, so that the jar to the machine and injury to the work due to tool-impact will also be avoided. When the piston bottoms or reaches the end of its cylinder the bed will be moved forward with a positive driving stroke, and liquid will have been forced into the cylinder 30 so that the parts will be in position to have a similar operation when the other reversal takes place and the pinion 24 is brought into operation. It will be seen therefore that an initially yielding, but finally solid connection is provided.

In the construction as thus far described, it is to be understood that I have shown my invention applied to the particular form of driving mechanism illustrated in the first sheet of drawings for the purpose of illustration merely, and that my invention is also applicable to any form of main driving mechanism in which a rack is used for moving the bed either forward or backward. For example as shown in Figs. 4 and 5, I have illustrated a construction in which a single driving pinion is used, and which may be turned in opposite directions by shifting the belts onto tight and loose pulleys in the ordinary manner. Referring to these figures, 40 designates the bottom side of a planer table, and 41 and 42 designate uprights or parts of the frame-work of the machine. The driving connections illustrated in these figures comprise a shaft 43 journaled in the uprights 41 and 42. Secured upon the shaft 43 are tight pulleys 44 and 45, and a loose pulley 46. It is to be understood that these tight and loose pulleys are to coöperate with shifting belts in the ordinary manner. At its inner end the shaft 43 is provided with a driving pinion 47 which meshes with a loose rack 48 which may be dove-tailed into the planer table as in the constructions before described. Carried by the loose rack 48 is a piston rod 49 carrying a piston 50 mounted on a cylinder 51 secured to the bed. The opposite ends of the cylinder 51 may, if desired, be connected by a pipe 52, and the flow of air or liquid from one end of the cylinder to the other end of the cylinder may be regulated by a throttle valve 53. The operation of this form of construction is substantially the same as that before described, except that the table is moved both forward and back by a single driving rack, and a single cylinder and piston are used for yieldingly connecting the rack for both its forward and backward strokes, and in this construction, as before described, the rate of motion may be regulated by the throttle valve, although, of course, it may be understood that the piston can be fitted loose enough, or may have provision for sufficient leakage so that no piping

would be required. Although I have called this a single cylinder, it will be obvious that its two ends constitute in effect opposed cylinders, and that each has a piston therein.

5 I am aware that numerous changes may be made in practicing my invention by those who are skilled in the art, and that my invention may be applied to many different forms of table reciprocating mechanisms. 10 That is to say while I have illustrated my invention applied to a form of driving mechanism in which two oppositely revolving driving pinions are used in connection with two independently movable racks, it is 15 obvious that my cushioning device may be used as a yielding connection with other forms of main driving mechanism. I do not wish, therefore, to be limited to the construction I have herein shown and described, 20 but

What I do claim and desire to secure by Letters Patent of the United States is:—

1. The combination of the part to be reciprocated, a driving pinion, a rack, and a 25 yielding driving connection between the rack and reciprocated part, comprising a piston and a fluid cylinder having a restricted outlet therefrom through which liquid is forced alternately in both directions 30 by the travel of the piston.

2. The combination of the part to be reciprocated, a driving mechanism, and a yielding driving connection between the reciprocated part and its driving mechanism 35 comprising two opposed fluid cylinders, a restricted pipe or passage connecting the cylinders, and a piston mounted in each of said cylinders.

3. The combination of the part to be reciprocated, a driving mechanism, and a 40 yielding driving connection between the reciprocated part and its driving mechanism comprising two opposed fluid cylinders, a pipe or passage connecting said cylinders, 45 means for adjustably throttling the flow of fluid through said pipe, and a piston moving in each of said cylinders.

4. The combination of the table to be reciprocated, two racks, a driving mechanism 50 for the racks comprising oppositely rotating shafts, a driving pinion on each of said shafts engaging one of said racks, a clutch for each of said driving pinions, a connection for simultaneously moving the clutches 55 to disengage one clutch when the other clutch is thrown into operation, and yielding connections between the racks and table comprising two opposed cylinders secured near opposite ends of the table, a pipe connecting said cylinders, and a piston moved 60 by each rack, said pistons being mounted in the cylinders.

5. The combination of a reciprocating bed, a driving pinion, a rack, and an ini-

65 tially yielding but finally solid driving connection between the rack and bed, said connection comprising a piston and a fluid cylinder having an outlet through which liquid is forced by the piston until a solid bearing 70 is reached between the piston and cylinder, whereupon a solid mechanical connection is formed between the rack and bed during further travel of the bed.

6. The combination of a reciprocating bed, a driving pinion, a rack, and an initially yielding but finally solid driving connection between the rack and bed, said connection comprising a piston and a fluid cylinder having an adjustable outlet through which liquid is forced by the piston until a 80 solid bearing is reached between the piston and cylinder, whereupon a solid mechanical connection is formed between the rack and bed during the further travel of the bed.

7. The combination of a reciprocating 85 part, a driving member therefor, and an initially yielding but finally solid driving connection between the driving member and reciprocating part, said connection comprising a piston and a fluid cylinder having an 90 outlet through which liquid is forced by the piston until a solid bearing is reached between the piston and cylinder, whereupon a solid mechanical connection is formed between the driving member and reciprocating 95 part during the further travel of said reciprocating part.

8. The combination of a reciprocating driven part, a driving and reversing part, and connected yielding connections for preventing a sudden shock at the beginning of both the forward and reverse strokes and for transmitting the motion of the driving part 100 positively and unyieldingly to the driven part, during the greater part of the forward 105 and reverse strokes.

9. The combination of a driven part, a driving and reversing part, and two connections for preventing a sudden shock at the beginning of both the forward and reverse strokes, said connections being connected with each other, and each one serving as a solid connection when the other is 110 in condition to yield.

10. The combination of a reciprocating 115 driven part, a driving and reversing part comprising two movable elements, a piston rigidly connected with each of said elements, a cylinder for each of said pistons, and a connection between said cylinders, whereby 120 a fluid may be forced from one to the other during the beginning of the forward stroke, and in the reverse direction during the beginning of the reverse stroke to relieve a sudden shock at the beginning of each of the 125 strokes.

11. The combination of a reciprocating driven part, a driving part comprising two

independently movable elements, a piston rigidly connected with each of said elements, said pistons being located on opposite ends of said elements, a cylinder for each of said 5 pistons, and means for restricting the passage of fluid to and from each cylinder.

In testimony whereof I have hereunto set

my hand, in the presence of two subscribing witnesses.
